UNITED STATES PATENT OFFICE.

SAMUEL MASTIN STEVENS, OF MANCHESTER, ENGLAND.

HAND FIRE-EXTINGUISHER.

No. 830,380.

Specification of Letters Patent.

Patented Sept. 4, 1906.

Application filed May 25, 1904. Serial No. 209,750.

To all whom it may concern:

Be it known that I, SAMUEL MASTIN STEVENS, a citizen of the United States of America, residing at Manchester, in the county 5 of Lancaster, England, have invented Improvements in Hand Fire-Extinguishers, of which the following is a specification.

This invention has reference to improvements in hand fire-extinguishers, objects being to strengthen the discharge-nozzle and improve its spraying effect on the liquid being discharged to enable the sealing-cap to be readily secured to the nozzle around the discharge-opening and to provide means where- 10 by it can be readily wrenched off and quickly removed when the extinguisher is held in the hand in the proper position for throwing and spraying the liquid and to facilitate the closing of the filling-opening.

20 Figure 1 of the accompanying illustrative drawings shows in side elevation the upper portion of a fire-extinguisher constructed according to this invention with the device for facilitating the removal of the cap. Fig. 2 25 is a plan thereof without the said device. Fig. 3 is a central vertical section, and Fig. 4 is a perspective view of the cap-removing device removed from the extinguisher.

The tubular body or container is provided 30 with a tapering nozzle *a*, that is formed with a series of longitudinal hollow ribs or corrugations *b*, terminating close to the discharge-opening *c*, which is preferably somewhat larger than usual and is disposed eccentrically of the body of the extinguisher. These ribs are spaced from each other and form liquid-conduits extending approximately from the body of the retainer to the discharge-opening to convey the liquid toward the 35 toothed edge, hereinafter described, surrounding said discharge-opening. Each conduit is approximately of uniform depth and width throughout its length to permit a practically undisturbed flow of the liquid, where- 40 by means of the jets from the various conduits impinging on each other an effective spraying action is attained. Upon the nozzle *a* is soldered or secured a ring *d*, which may rest on the ends of the ribs or corruga- 45 tions, although in the example illustrated it is shown slightly above them. The hollow ribs or corrugations *b* serve as conduits for the fire-extinguishing liquid during its discharge by the jerking forward of the extinguisher toward the burning material and not 50 only improve the spraying effect of the nozzle,

but also strengthen it, so that while discharge is taking place it can be pushed among goods that are on fire without risk of it becoming damaged. Teeth or projections 60 *e* on the end of the nozzle project through the ring *d*. Instead of being turned inwardly, as heretofore, they are set so as to incline outwardly and have the effect of breaking up 65 the stream of liquid issuing from the opening *c* and causing a wider distribution of the spray than usual. The cap *f* is shown formed with an outwardly-extending flange that constitutes the ring *d*.

A hanger *g*, whereby the extinguisher can 70 be suspended from any suitable support, is secured to the nozzle *a* independently of the cap *f*, so that the latter can be secured in place with solder that is easily broken and without wires or the like which connect the 75 hanger to the tube-like container *h* of the extinguisher and necessitate the turning over of the extinguisher to enable its cap to be removed. To facilitate the closing of the filling-opening in the end of the cap *f*, it is 80 formed with an annular recess *i*, the edge of the closing disk or plate *j* resting in said recess and its outer face being preferably flush with the surface of the cap.

To enable the cap to be easily wrenched 85 off from the nozzle and readily removed, the extinguisher is provided with a lever *m*, arranged to normally extend in juxtaposition to a wall of the nozzle and adapted to engage the cap *f* and ring *d* in such way that when 90 the lever is pulled away from the wall of the nozzle the cap and ring will be wrenched off. This lever *m* is provided with a pivoted handle or extension *n*, adapted to be turned out of the way into a position in which it is located 95 over the lever *m*, its outer end then resting on a shoulder *o* of the lever. (See Fig. 1.) One end of the lever *m* is formed as a ring *p*, that fits over the cap *f*, and with a tooth *q*, that engages the ring *d*, which is recessed at 100 *r*, so that when the tooth *q* is in line with the recess *r* the ring *p* can be seated on the ring *d*, when the lever can be turned partly around the cap, so as to cause the tooth *q* to engage with the ring *d*, the body portion of 105 the lever being brought to the front of the extinguisher. A grooved lug or projection *s* may be provided at the front of the nozzle *a*, as shown by dotted lines in Fig. 1, into which the lever *m* may be sprung, so as to 110 cause it to be retained in this position. The arrangement is such that when the lever is

forcibly raised; which can easily be effected by grasping the pivoted extension *n* thereof, the ring *d* and cap *f* are wrenched off the nozzle.

5. What I claim is—

1. A hand fire-extinguisher comprising a tube-like container having a tapered end nozzle terminating in the discharge-mouth, and detachable closing means for said mouth, 10 said nozzle formed with a series of spaced internally-hollow ribs arranged approximately throughout the length thereof and converging toward said mouth and forming liquid-conduits, each of approximately uniform 15 depth throughout, whereby the liquid is jetted from the outer ends of the conduits, substantially as described.

2. A hand fire-extinguisher comprising a tube-like container having a tapered discharge-nozzle with a toothed edge surrounding its discharge-opening, said nozzle formed with longitudinal hollow ribs which terminate close to said discharge-opening and form liquid-conduits extending approximately 25 from the body of the container to convey the liquid to said toothed edge.

3. A fire-extinguisher having a nozzle with an unobstructed discharge-opening, a series of longitudinally-extending teeth or projections arranged around said opening and deflected outwardly or radially therefrom, and a detachable closing-cap on the end of said nozzle, substantially as described.

4. A hand fire-extinguisher having a nozzle terminating in a discharge-opening, a closing-cap for said opening and a lever adapted to engage said cap and arranged to normally extend in juxtaposition to a wall of said nozzle and whereby when the lever is 40 moved away from said wall the cap is removed from the nozzle.

5. A hand fire-extinguisher having a nozzle terminating in a discharge-opening, a closing-cap for said opening, and separate 45 and independent means adapted to engage said cap and whereby it can be removed from the nozzle, substantially as set forth.

6. A hand fire-extinguisher having a nozzle terminating in a discharge-opening, a detachable closing-cap secured to said nozzle to close said discharge-opening and having an exterior projection, separate and independent detaching means adapted to fit said nozzle and engage said projection for removing 55 said cap, substantially as described.

7. A hand fire-extinguisher having a nozzle terminating in a discharge-opening, a detachable closing-cap secured upon said nozzle around the discharge-opening thereof and 60 having an exterior recessed ring, a lever formed with one end adapted to embrace said cap and with a tooth adapted to engage said cap-ring.

8. A hand fire-extinguisher having a nozzle terminating in a discharge-opening, a de-

tachable cap secured upon said nozzle around the discharge-opening thereof, and having an exterior ring, and a lever formed to embrace said cap and engage said cap-ring, said lever being formed with a pivoted handle.

9. A hand fire-extinguisher having a nozzle terminating in a discharge-opening, a detachable cap provided with a ring having a recess in its edge, secured upon said nozzle around the discharge-opening thereof, a lever 75 formed with one end adapted to embrace said cap and with a tooth adapted to engage said cap-ring when the lever is turned partly around the nozzle after being placed with its end embracing the cap and its tooth in line with the recess of said cap-ring, said lever being formed with a pivoted handle adapted to be turned back out of the way onto the lever.

10. A hand fire-extinguisher having a discharge-opening and supporting means, detachable sealing means for said opening independent of said supporting means, and an independent manually-operated lever fitted on and for removing said sealing means, substantially as set forth.

11. A hand fire-extinguisher having a discharge-nozzle formed with longitudinal hollow ribs or corrugations which terminate close to the discharge-opening of said nozzle, spraying teeth or projections on the end of 95 said nozzle, a detachable closing-cap provided with an exterior recessed ring and formed with a filling-opening through its end and with an annular recess around said filling-opening, a closing disk or plate the edge of which is adapted to rest in said recess and the outer face of which is flush with the surface of said cap, a lever formed with a ring portion adapted to engage said cap and with a tooth adapted to engage said cap-ring 105 when the lever is turned partly round the nozzle after being placed with its ring over the cap and its tooth in line with the recess of said cap-ring.

12. A hand fire-extinguisher comprising an elongated tube-like container having a tapered end nozzle terminating in a discharge-opening, a detachable closing-cap fitted and secured on the end of the nozzle over said opening, a hand detaching-lever fitted to and depending from said cap, and means for supporting said container in a vertical position independently of said cap and lever, substantially as described.

13. A tubular hand fire-extinguisher having a nozzle of tapering form with a discharge-opening at the smaller end, spaced internally-hollow ribs extending lengthwise of said nozzle and forming liquid-conduits converging toward and extending approximately to said opening, and a detachable cap closing said opening.

14. A tubular hand fire-extinguisher having a nozzle of tapering form with a discharge-opening at the smaller end and dis-

- posed eccentrically as regards the axis of the tube, internally-hollow ribs extending lengthwise of said nozzle and converging toward said opening, a hanger attached to the least 5 inclined side of said nozzle, a detachable cap closing said opening, and a lever engaging said cap and lying close to the wall of said nozzle and whereby said cap can be wrenched off.
- 10 15. A tubular hand fire-extinguisher having a nozzle of tapering form with a discharge-opening, a hanger attached to said nozzle, a detachable cap closing said opening and formed with a flange having a recess in 15 its edge, a lever formed with one end adapted to embrace said cap and with a tooth adapted to engage said cap-flange when the lever is turned partly around the nozzle after being placed with its end embracing the cap and its 20 tooth in line with the recess of said flange, and means for holding said lever in position with its tooth engaging said flange, close to that side of the nozzle opposite to said hanger.
- 25 16. A hand fire-extinguisher comprising an elongated tube-like container having a tapered end nozzle terminating in a discharge-opening, a detachable closing-cap fitted and secured on the end of said nozzle and over said opening and provided with detach- 30 ing means comprising a handle projecting exteriorly therefrom and whereby the cap can be wrenched and tilted from the nozzle by hand, and a hanger independent of said cap and means, and whereby the container can 35 be suspended in an upright position, substantially as described.
17. A tubular hand fire-extinguisher having a nozzle of tapering form with an unobstructed discharge-opening at the smaller 40 end and disposed eccentrically as regards the axis of the tube, having a surrounding toothed edge and internally-hollow ribs forming liquid-conduits extending lengthwise of said nozzle and converging toward said open- 45 ing.

Signed at Manchester, England, this 30th day of April, 1904.
